BARREL RACK

Filed March 17, 1926

Patented Apr. 3, 1928.

UNITED STATES PATENT OFFICE.

AUGUST G. SCHOESSLER, OF RELIANCE, SOUTH DAKOTA.

BARREL RACK.

Application filed March 17, 1926. Serial No. 95,362.

This invention relates to store furniture and more particularly to a rack adapted to support a barrel from which a liquid is to be dispensed.

One object of the invention is to so form the rack that it may be readily engaged with a barrel and the barrel supported in substantially a horizontal position so that the contents may be dispensed through a faucet inserted in one of its heads.

Another object of the invention is to provide the rack with pivotally connected sections extending in diverging relation to each other and terminating in hooks which may have firm gripping engagement with opposite ends of the barrel when the sections are drawn toward each other.

Another object of the invention is to so form the rack that it may accommodate itself to barrels of different sizes.

Another object of the invention is to provide the rack with a prop, by means of which the rack may be firmly supported and angular adjustment of the rack and barrel effected so that, when only a small quantity of liquid remains in the barrel, it may be tilted to such an angle that the liquid may flow out.

Another object of the invention is to produce a barrel rack formed almost entirely of angle metal and, therefore, relatively light in weight but very strong in its construction.

This invention is illustrated in the accompanying drawing, wherein

Figure 1 is a view in side elevation showing a barrel supported upon the improved rack;

Fig. 2 is a top plan view of the rack, and

Fig. 3 is a fragmentary view illustrating a modified construction.

The barrel rack forming the subject-matter of this invention includes sections which are indicated in general by the numerals 1 and 2 and are pivotally connected at their inner ends so that they may be swung towards and away from each other into and out of gripping engagement with opposite ends of a barrel. The side bars 3 and 4 of the pivoted sections are formed of angle metal and each has its vertically extending side flange cut away adjacent its outer end so that its inwardly extending flange protects beyond the outer end of its side flange. These projected end portions of the inwardly extending flanges are bent to form hooks 5, and from an inspection of Fig. 1 it will be readily

seen that these hooks may have firm gripping engagement with the end portions of a barrel B to be supported upon the rack. Bracing strips 4' extend between the side bars of the frame section 1 and may also be provided between the side bars of the section 2 if so desired. In the form illustrated in Figs. 1 and 2, the inner ends of the sections 1 and 2 are pivotally connected by a rod 6 which extends between the side bars and has its end portions passed through aligned openings formed in the overlapped inner end portions of the side flanges of the bars 3 and 4. At one end the pivot rod is formed with a head 7 and drilled to receive a pin 8 and at its other end is threaded and carries securing nuts 9 which securely hold the rod in place and prevent it from working out of engagement with the vertical flanges of the side bars 3. It will be obvious that if desired the rod could also have its other end portion threaded and nuts applied thereto instead of being formed with a head 7. Cross bars 10 which are also formed of angle metal 80 extend between the side bars 3 and 4 and each includes a substantially vertically extending flange and an inwardly extending flange. One of these flanges has its end portions extending beyond the ends of the other 85 flange and bent to form ears 11 which are secured against the inner faces of the flanges 3 and 4 by fasteners 12 which may be either small bolts or rivets. The cross bars should, however, be permitted to turn about their 90 fasteners 12 so that, when the sections are swung towards and away from each other, the cross bars will be free to turn and prevent binding of the drawbar 13 in the openings formed in the vertically extending flanges of 95 the cross bars. The drawbar is formed at one end with a head 14 and has its other end portion threaded to receive an adjusting nut 15. When the adjusting nut is tightened, a pulling action is exerted upon the 100 drawbar and the sections of the stand will be drawn toward each other for firm gripping engagement with the barrel. The support or prop 16 by means of which the stand is supported in the position shown in 105 Fig. 1 is of a U-shaped construction and has its arms 17 pivotally mounted upon the outer end portions of the bolts 12. The prop may, therefore, be swung towards and 110 away from the section 1 and cause the barrel to be supported in either a substantially horizontal position, as shown in Fig. 1, or

tilted so that a small quantity of liquid in the barrel may readily flow out of the same through the faucet 18. Latches 19 are provided to engage pins 20 carried by the arms 5 17 of the prop and retain the prop in a set position.

Instead of pivotally connecting the inner ends of the sections 1 and 2 through the medium of a pivot rod 6, a bridge, such as 10 shown in Fig. 3 and indicated by the numeral 21, may be employed. The bridge is formed of angle metal and has the end portions of one of its flanges extending beyond the ends of its second flange and bent to form 15 ears 22 which engage the inner faces of the vertically extending side flanges of the side bars of section 1. Bolts or other suitable fasteners 23 pass through the ears 22 and vertically extending flanges of the side bars 20 so that the side bars are pivotally connected to the end portions of the bridge. It will, of course, be obvious that if so desired a single elongated bolt may be employed in 25 place of separate bolts.

25 When the rack is to be applied to a barrel, the barrel is preferably set on end and tilted somewhat so that the hooks 5 of the section 2 may engage with the lower end of the barrel. The hooks of the section 1 are then engaged with the upper end of the barrel and the securing nut 15 tightened a sufficient extent to retain the hooks in firm gripping engagement with the barrel. The barrel may now be tilted towards a horizontal position 30 and as it is tilted the pivotally connected inner ends of the two sections 1 and 2 will engage the ground or floor and constitute a fulcrum upon which the frame may be readily tilted to the position 35 shown in Fig. 1. When in this position, it will be supported by the prop 16 and as the greater portion of the weight is disposed over the section 1, it will be obvious that the barrel will not have a tendency to return to 40 its original vertical position. The faucet 18 which will preferably be inserted while the barrel is in the vertical position may now be turned on and the liquid contents of the barrel may readily flow from the faucet into a 45 suitable receptacle. When the level of the liquid contents of the barrel has been reduced to such an extent that the liquid does not flow properly through the spigot, the prop 16 may be swung outwardly a sufficient 50 distance to lower the end of the barrel in which the spigot is inserted and the contents of the barrel will flow towards this lower end and readily pass outwardly through the spigot. When the barrel is emptied, the rack 55 may be readily removed and applied to another barrel.

60 Having thus described the invention, I claim:

1. A barrel rack comprising barrel-engaging

sections each including side bars and a cross 65 bar connecting its side bars, the side bars of one section having their inner ends pivotally connected with the side bars of the other section and each section having outer ends of its side bars provided with hooks for engaging 70 opposite ends of a barrel, the pivotally connected ends of said side bars constituting a fulcrum for the rack, a draw rod extending through alined openings formed in the cross bars of said sections and having one end 75 formed with a head to engage the cross bar of one section and its other end portion threaded, a nut upon the threaded portion of said rod for engaging the cross bar through which the threaded end portion of the rod 80 passes and drawing said sections towards each other and retaining the hooked ends of their side bars in gripping engagement with a barrel, and a prop carried by the side bars of one section for supporting the rack at a 85 desired angle of inclination.

2. A barrel rack comprising barrel-engaging sections including side bars and cross bars formed of angle metal, the side bars having vertically extending side flanges and other flanges extending inwardly therefrom and projecting beyond the outer ends of the side flanges and bent to form barrel-engaging hooks, the inner ends of said sections having the side flanges of their side bars pivotally 90 connected to mount the sections for swinging towards and away from each other, said cross bars being formed of angle metal and each having one flange extending beyond the ends of its other flange and bent 95 to form ears, said ears being secured to the vertically extending flanges of said side bars, and a draw rod passed through openings in 100 said cross bars and adapted to hold the sections in gripping engagement with a barrel.

3. A barrel rack comprising barrel-engaging sections including side bars and cross bars formed of angle metal, the side bars having vertically extending side flanges and other flanges extending inwardly therefrom and projecting beyond the outer ends of the side flanges and bent to form barrel-engaging hooks, the inner ends of said sections having the side flanges of their side bars pivotally 105 connected to mount the sections for swinging towards and away from each other, a draw rod extending through openings in 110 said cross bars and having a head at one end and a nut threaded upon its other end portion and adapted to draw the sections towards each other into gripping engagement with the ends of a barrel disposed longitudinally between the sections, and a bridge extending between and secured to the inner 115 ends of the side bars of one section to brace 120 the same against transverse movement.

In testimony whereof I affix my signature,
AUGUST G. SCHOESSLER. [L. s.]
